(57) **CLAIM**

The ornamental design for a container for packaging cosmetics, as shown and described.

DESCRIPTION

FIG. 1 is an exploded view of a container for packaging cosmetics showing the new design.

FIG. 2 is a front, top, and right-side orthographic view of the container for packaging cosmetics of FIG. 1 shown without the cap and shown at an enlarged scale.

FIG. 3 is a front elevation view thereof.

FIG. 4 is a rear elevation view thereof.

FIG. 5 is a right-side elevation view thereof.

FIG. 6 is a left-side elevation view thereof.

FIG. 7 is a top plan view thereof.

FIG. 8 is a front, top, and right-side orthographic view thereof shown with the cap in place.

FIG. 9 is a front elevation view thereof.

FIG. 10 is a rear elevation view thereof.

FIG. 11 is a right-side elevation view thereof.

FIG. 12 is a left-side elevation view thereof; and,

FIG. 13 is a top plan view thereof.
